FOREIGN PATENT DOCUMENTS

KR 3020190014305 * 3/2019

Primary Examiner — Khawaja Anwar*Assistant Examiner* — Julice Seung Eun Oum**CLAIM**

I claim: The ornamental design for a golf club head, as shown and described.

DESCRIPTION

FIG. 1 is a top perspective view of a golf club head; FIG. 2 is a bottom perspective view of the golf club head of FIG. 1;

FIG. 3 is a top view of the golf club head of FIG. 1;

FIG. 4 is a bottom view of the golf club head of FIG. 1;

FIG. 5 is a front view of the golf club head of FIG. 1;

FIG. 6 is a rear view of the golf club head of FIG. 1;

FIG. 7 is a heel side view of the golf club head of FIG. 1; and,

FIG. 8 is a toe side view of the golf club head of FIG. 1. The broken lines shown on the drawing figures form no part of the claimed design.
